ucts Corporation, Brooklyn, N. Y., a corporation
of New York

Application February 26, 1942, Serial No. 105,989

Term of patent 7 years

To all whom it may concern:

Be it known that we, Philip A. Derham and Jesse H. Newport, Jr., citizens of the United States and residents of Rosemont, in the county of Montgomery and State of Pennsylvania, have invented a new, original, and ornamental Design for a Combined Container Cap and Eye-cup, of which the following is a specification, reference being had to the accompanying drawing, forming part thereof.

Fig. 1 is a front view of a combined container cap and eyecup showing our new design.

Fig. 2 is a side view of the same.

Fig. 3 is a bottom plan view of the same.

We claim:

The ornamental design for a combined container cap and eyecup, substantially as shown.
